(57) **CLAIM**

The ornamental design for a set of power training palm paddles, as shown and described.

DESCRIPTION

FIG. 1 is a top elevation view of a single paddle shown separately for convenience of illustration;

FIG. 2 is a top perspective view of FIG. 1;

FIG. 3 is a top perspective view showing the surgical tubing;

FIG. 4 is a bottom perspective view showing the surgical tubing;

FIG. 5 is a top elevation view of power training palm paddles of FIG. 1, with hand mounted to training paddle;

FIG. 6 is a bottom elevation view of power training palm paddles of FIG. 1, with a view of the palm of the hand shown through the centrally located hole;

FIG. 7 is a top elevation view of a set of power training palm paddles showing the right paddle as a mirror image of the left paddle;

FIG. 8 is a front elevation view;

FIG. 9 is a rear elevation view;

FIG. 10 is a left side elevation view; and,

FIG. 11 is a right side elevation view.

The broken lines in the Figures show portions of the power training palm paddles that form no part of the claimed design.

The shade lines in the Figures show contours and not surface ornamentation.
